WEB FEEDING MECHANISM FOR PACKAGE FORMING MACHINES

John G. Vergobbi, Quincy, Mass., assignor to Pneumatic Scale Corporation, Limited, Quincy, Mass., a corporation of Massachusetts

Application October 1, 1948, Serial No. 52,257

5 Claims. (Cl. 93—12)

1

This invention relates to web feeding mechanism particularly adapted for use in a package forming machine.

The invention has for an object to provide a novel and improved web feeding mechanism wherein provision is made for controlling the leading portion or free end of a relatively thin, lightweight flexible web of sheet material as it is being advanced into a predetermined position, in a simple and highly efficient manner.

With this general object in view and such others as may hereinafter appear the invention consists in the web feeding mechanism and in the various structures, arrangements and combinations of parts hereinafter described and particularly defined in the claims at the end of this specification.

In the drawings illustrating the preferred embodiment of the invention, Fig. 1 is a side elevation, partly in cross-section, of a package forming machine provided with web feeding mechanism embodying the present invention; Fig. 2 is a front elevation as viewed from the line 2—2 of Fig. 1; and Fig. 3 is an elevation of the web feeding mechanism as viewed from the line 3—3 of Fig. 1.

In general the present invention contemplates novel web feeding mechanism particularly adapted for feeding a web of relatively thin lightweight flexible sheet material from a supply thereof and into operative position to be severed to form an individual sheet or blank of container forming material. The invention is herein illustrated as embodied in a container forming machine for forming a lined carton in which the sheet material is fed into operative position to be wrapped about a forming block to form a bag or inner liner for a package. Inasmuch as the details of such container forming machines are well known and of themselves constitute no part of the present invention, only sufficient portions of such machines are herein illustrated and described to enable the present invention to be understood.

Prior to the present invention difficulty has been encountered in feeding relatively thin lightweight sheet material such as a thin paper web, for example, into a definite and predetermined position relative to the usual blank forming cutter and to the forming block, because of the relatively light weight and instability of the material and, in practice, the free end of such material often would curl up, wrinkle, or fold over when it engaged the supporting elements upon which it was supported as it was advanced, thus

2

interrupting the successful and practical operation of the machine.

In accordance with the present invention, provision is made for controlling the movement of the leading portion of the sheet material to be fed as it is being advanced by causing a stream of air to flow along the underside of the leading portion of the sheet in the direction of movement of the sheet. The air stream is directed thereby in a direction parallel to the underside of the sheet and thus insuring the proper relation of the sheet to the supporting elements upon which it is being advanced.

Referring now to the drawings, 10 represents a forming block or mandrel forming a part of a container forming machine having a plurality of such forming blocks, only one of which is shown. The blocks are arranged to be intermittently moved to the various lining and carton forming stations of the machine. In general, in the operation of such machines, the sheet material is advanced beneath the forming block and severed to form a lining blank, and the lining blank is then folded about the forming block to form a tube. At a succeeding station of operation, portions of the lining blank extending beyond the end of the forming block are folded and sealed to form the bottom end of the lining bag. At subsequent stations of the machine an outer blank or carton may be wrapped about the lining bag on the block in a similar manner, whereupon the composite liner and carton may be stripped from the forming block ready to be filled and the top sealed.

35 In the illustrated embodiment of the invention, a web of sheet material 12 is unwound from a supply roll 14 thereof by a pair of intermittently operated cooperating rollers 16, 18 and fed into operative position beneath the forming block 10 and on top of supporting elements herein shown as comprising vertically reciprocal blank supporting and folding means of well-known construction including a bottom plate 20 and pairs of side brackets 22 and 24 arranged to be subsequently 40 elevated to wrap the blank about the bottom and two sides of the block 10 as illustrated in Fig. 2. According to the present invention the upper surfaces of the brackets 22 and 24 are provided with upstanding spaced parallel ribs bridging the brackets and extending in the direction of web movement. As shown in Fig. 2 these ribs may be provided by attaching wires or rods 27 to the brackets 22 and 24 as by welding or brazing. In practice the bottom plate 20 is elevated to present 45 and retain the blank in firm engagement with the

undersurface of the block, while the side brackets 22 and 24, and rods 27 continue upwardly to wrap the blank against the sides of the block, leaving opposed side wall portions 26, 28 of the blank extended vertically beyond the top surface of the block as illustrated. Thereafter the extended portions of the blank are folded in overlapping or contiguous relation and sealed to form a tubular bag portion, and then the extended end portions of the tube are folded and sealed to close the bottom of the bag in the usual manner.

The web feed rollers 16, 18 may and preferably will be intermittently operated to feed a predetermined length of the thin web material onto the folding plates each cycle of operation, and provision is then made for severing the leading portion of the web to form a lining blank. As herein shown, the severing mechanism may comprise a pair of cooperating cutting elements including a fixed knife blade 30 and a movable blade 32 as illustrated in Fig. 1.

In accordance with the present invention provision is made for controlling the leading or forward portion of the web extending beyond the feed rollers 16, 18 to maintain the same extended in a substantially horizontal position parallel to the supporting elements comprising the folding brackets and rods and, as herein shown, this is accomplished by projecting a plurality of streams of air along the underside of the sheet between it and the brackets and along the channels between ribs 27 in the direction of movement of the sheet and parallel thereto as it is being fed forward by the feed rollers 16, 18. The compressed air may be supplied from any usual or preferred source, and as herein shown, is arranged to pass through a plurality of relatively small spaced tubes or jets 34 connected at one end to an air supply pipe 36 disposed below and in front of the feed roller 18. The tubes 34 extend upwardly from the supply pipe and are curved around the feed roller 18 and extended horizontally to assume a position parallel to and immediately beneath the web being advanced. As best shown in Fig. 3, the tubes 34 are arranged to fit into spaced peripheral grooves 38 formed in the feed roller 18 so that the upper surfaces of the tubes are substantially flush with the outside diameter of the feed roller, as illustrated, to permit the web to pass over the tubes as it is advanced by the rollers, the horizontally extended portions of the tubes forming a support for the leading edge of the web as it is advanced beyond the feed rollers onto the folding means. The open ends of the tubes 34 may terminate at a point immediately in front of the cutter blades, as shown.

With this construction it will be observed that in the operation of the machine the streams of air projected from the tubes 34 will necessarily pass between the web 12 and brackets 22 and 24, being guided by the ribs 26 to move along the channels between the ribs. By confining the streams in this manner their velocity is preserved and turbulence prevented. The velocity of the streams below web 12 produces a suction effect holding the free end of the web down on the crests of the ribs and preventing upward curl of the leading edge, particularly when web 12 is of very thin material. This effect is especially pronounced near the ends of tubes 34 and where the air streams pass over the brackets 22 and 24.

From the above description of the preferred embodiment of the invention it will be seen that in the operation of the machine the web of container forming material 12 is intermittently ad-

vanced into operative position to dispose the leading blank forming portion of the web beneath the forming block 10 and into operative relation to the severing blades 30, 32 to form successive cut-to-length blank sheets adapted to be wrapped about successive forming blocks 10 to form the containers and that during the advance of the leading portion of the web beyond the feed rolls 16, 18, the web is maintained in a horizontally extended position by the air streams caused to flow between the undersurface of the web and the upper surfaces of the folding elements 20, 22, 24 and 27. The cut-off operation may occur immediately upon the web coming to rest and immediately thereafter the folding elements may be elevated to perform the wrapping operation. While the air streams may be controlled in any usual or preferred manner to start and stop the flow of air in timed relation to the advancement of the web, it will be observed that in the illustrated embodiment of the invention the movable cutter blade 32 is disposed in a position to cut off or divert the flow of air from the jets 34 during the severing operation and immediately thereafter or simultaneously therewith the folding plates are operated to carry the severed blank upwardly out of the influence of the air streams when the jets are subsequently exposed by the cutter blade.

While the present web feeding mechanism may be used with advantage for feeding and controlling the leading portion of relatively thin, non-rigid, lightweight paper, cellophane or other sheet material, it will be apparent that the invention may be used with advantage in feeding heavier and more rigid types of flexible sheet material to assist in controlling the advance of the leading portion.

While the preferred embodiment of the invention has been herein illustrated and described, it will be understood that the invention may be embodied in other forms within the scope of the following claims.

Having thus described the invention, what is claimed is:

1. In apparatus of the character described, in combination, feeding mechanism comprising a pair of intermittently operated feed rolls arranged to advance a predetermined length of a web container forming material, folding means which the advanced portion of the web is passed, and means for maintaining said advanced portion in a fully extended condition and in operative relation to said folding means during the advancing movement comprising a plurality of air jets arranged to direct a plurality of streams of air along the undersurface of said advanced portion substantially parallel to and in the direction of movement of the web and upstanding parallel ribs on said means defining channels for said streams of air extending in the direction of movement of said web.

2. In apparatus of the character described, in combination, feeding mechanism comprising a pair of intermittently operated feed rolls arranged to advance a predetermined length of a web of container forming material, folding means over which the advanced portion of the web is passed, and means for maintaining said advanced portion in a fully extended condition and in operative relation to said folding means during the advancing operation, comprising a plurality of air jets arranged to direct a plurality of streams of air along the undersurface of said advanced portion substantially parallel to and in the direction of movement of the web,

and means for interrupting said air streams after said predetermined length has been advanced and upstanding parallel ribs on said means defining channels for said streams of air extending in the direction of movement of said web.

3. In apparatus of the character described, in combination, a forming block, feeding mechanism comprising a pair of intermittently operated feed rolls arranged to advance a predetermined length of a web of container forming material, folding means upon which the advanced portion of the web is supported to be subsequently folded about the block, and means for maintaining said advanced portion in a fully extended condition and in operative relation to said folding means during the advancing operation comprising a means for directing a stream of air between the folding means and the undersurface of said advanced portion substantially parallel to and in the direction of movement of the web, and a cutter blade arranged to sever the advanced portion from the web, said blade being arranged to interrupt the air streams during the severing operation and upstanding parallel ribs on said means defining channels for said streams of air extending in the direction of movement of said web.

4. In apparatus of the character described, in combination, a pair of cooperating feed rolls comprising an upper and a lower roll arranged to advance a predetermined length of a web of flexible container forming material, means spaced from said rolls to receive and support material advanced by said rolls, and means for maintaining the advanced portion of the web in its fully extended condition during the advancing movement comprising a plurality of spaced air pipes arranged to direct a plurality of streams of air along the underside of said advanced portion substantially parallel to and in the direction of movement of said web, said lower feed roll having a plurality of spaced peripheral

grooves through which said air pipes are extended to bridge the space between said rolls and said material receiving and supporting means, said pipes being disposed along and in contact with the underside of the advanced portion of the web.

5. In mechanism for feeding a web of flexible sheet material, in combination, supporting means to receive said web, a plurality of upstanding spaced parallel ribs on said supporting means and extending in the direction of movement of said web, the crests of said ribs lying substantially in a single plane, means for advancing the web to and over said supporting means, and means for directing a plurality of streams of air along the undersurface of said advancing web in the direction of movement thereof and through the channels defined by said ribs whereby said web is pneumatically urged against the crests of said ribs and caused to lie thereover in a substantially flat and planar condition.
